UNITED STATES PATENT OFFICE.

JOE G. LADEN, OF IDABEL, OKLAHOMA, ASSIGNEE OF ONE-FOURTH TO JOHN W. DE WITT, ONE-FOURTH TO E. L. LADEN, AND ONE-FOURTH TO HARRY B. DRAKE, ALL OF IDABEL, OKLAHOMA.

BED.

1,108,515.

Specification of Letters Patent.

Patented Aug. 25, 1914.

Application filed May 23, 1914. Serial No. 840,566.

To all whom it may concern:

Be it known that I, Joe G. LADEN, a citizen of the United States, residing at Idabel, in the county of McCurtain and State of Oklahoma, have invented certain new and useful Improvements in Beds, of which the following is a specification, reference being had to the accompanying drawings.

This invention relates to improvements in beds, and has for its primary object to provide a simple and efficient means for mounting the spring supporting slats upon the side rails of the bedstead.

The invention has for a more specific object to provide in addition to a bedstead rail having an inwardly extending longitudinally channeled flange, a ribbed plate of improved form secured to the underside of the bed slat, the rib of said plate being designed at 20 for engagement in the channel of the bed rail.

The invention has for a further object to provide a device of the above character which is strong and durable in its construction, highly convenient and serviceable in practical use, and may be manufactured at small cost.

With the above and other objects in view, the invention consists in novel features of construction, combination, and arrangement of parts as will be hereinafter referred to and more particularly pointed out in the specification and claim.

For a full understanding of the invention, reference is to be had to the following description and accompanying drawings, in which—

Figure 1 is a perspective view showing a fragment of one of the side rails of the bedstead and one of the slats illustrating the preferred embodiment of my invention. Fig. 2 is a vertical section; and Fig. 3 is an inverted perspective view of one end of the bed slat illustrating the manner of securing the ribbed plate thereto.

Referring in detail to the drawing, 5 designates the bed rail which is formed with an upstanding outer vertical flange 6 and an inwardly projecting horizontal flange 7. This latter flange is formed midway be-

tween its longitudinal edges with a longitudinal groove or channel, indicated at 7.

The bed slat 8 is of the ordinary form and constructed of wood, and to one face of said slat at each end a sheet metal plate 9 is secured. This plate which is of substantially triangular form has its body portion cut out as indicated at 10 for the sake of lightness and economy in manufacture, and upon the wider end of said plate the U-shaped rib 11 is formed by pressing or stamping the same in a suitable die. Upon the edge of said plate at its wider end a prong or spur 12 is formed, and this spur is adapted to be bent over the end edge of 65 the wooden slat 8 and forced inwardly or embedded in the wood. It will therefore be seen that by the provision of this clenching spur, the rib plate is very rigidly and securely fastened upon the bed slat so that 70 the U-shaped rib 11 thereof will not be displaced from its proper position with respect to the slat by a distortion of the metal plate.

In the practical use of my invention, the ribs 11 on the ends of the bed slat 8 are 75 engaged in the longitudinal grooves or channels 7 of the respective side rails of the bed. The slats may be freely moved longitudinally upon the rail flanges while at the same time the liability of the ends of the slats 80 moving off of the flanges by a lateral shifting or turning movement of the slats is prevented by means of the ribs 11 as will be readily understood.

From the foregoing, it will be seen that I 85 have produced a very simple and inexpensive device which is of great convenience and serviceability in practical use and obviates the possibility of the ends of the slats moving off of the bed rails which will permit the bed springs to sag downwardly. In view of the extremely simple construction of the device, it will be manifest that the same can be produced at small manufacturing cost.

While I have above described the preferred form, construction, and arrangement of the several elements employed, it will be understood that the device is, nevertheless, susceptible of considerable modification 100

therein, and I therefore reserve the privilege of resorting to all such legitimate changes as may be fairly embodied within the spirit and scope of the invention as claimed.

What is claimed is:

The combination with a bedstead rail having an inwardly-projecting flange provided with a longitudinal channel, of a bed slat, and a sheet metal plate secured to one face

of said slat at its end and provided with a U-shaped rib spaced from the end of the bed slat adapted for sliding engagement in said channel.

In testimony whereof I hereunto affix my 15
signature in the presence of two witnesses.

JOE G. LADEN.

Witnesses:
